TOGGLE CATCH FOR BOXES

Harry D. Greenman, New York, N. Y.

Application April 15, 1942, Serial No. 439,113

4 Claims. (Cl. 292—114)

My invention relates to toggle catches for boxes and has particular reference to catches for locking wood boxes, especially of a type used for transporting ammunition.

My invention has for its object to provide a catch for boxes which can be easily and quickly snapped in place, drawing the lid of a box tightly to its edges, and which can be also quickly and easily opened.

Another object of my invention is to provide a catch which can be protected by a seal and cannot be opened without breaking the seal. My catch is so made for this purpose that screws with which it is fastened to the box cannot be removed while the catch is in a closed position and it cannot be opened without breaking the seal.

Another object of my invention is to provide a catch which can be opened and closed without any special or ordinary tools or devices, the connecting parts being of a toggle type so that they can exert great force in drawing the lid against the sides of the box.

Still another object of my invention is to provide a catch which can be made easily and cheaply of steel stampings and can withstand rough handling without being loosened or accidentally opened.

My invention is more fully described in the accompanying specification and drawing, in which:

Fig. 1 is a side view of my catch in a closed position;

Fig. 2 is a front view of the same;

Fig. 3 is a top view of the same;

Fig. 4 is a side view of my catch in an opened position; and

Fig. 5 is a diagrammatic view showing action of the device.

My toggle catch, as shown in Figs. 1 to 5 inclusive, consists of a keeper 1, which is attached to a lid 2 of a box 3 by screws 4, 5, and a base plate 6 attached to the side of the box by screws 7, 8. The keeper is bent at the middle so that the screws 4 pass through the upper side of the lid while the screw 5 is screwed into the edge of the lid at the side of a hook 9. The latter is engaged by a hook 10 of a locking latch 11. The lower end of the latch member has a loop 12 for a link 13 in the form of a rectangular wire ring. The upper portion of the ring is held in a loop 14 at the upper end of the member 6.

The upper portion 15 of the base plate 6 is bent outward so that the loop 14 is spaced from the box 3, while the latch member 11 is bent in-

ward at the middle, placing the loop 12 nearer the box 3 than the loop 14 when the latch member is in a locking position. With this arrangement a straight line 16 (Fig. 1), passing through the points of pressure between the hooks 9 and 10 at the top and loop 12 and ring 13 at the bottom, is nearer the box than the loop 14, so that while the latch member remains under tension, drawing the lid tightly against the box, a force is required to open the latch.

In order to facilitate opening the latch member, the latter is provided with an elbow 17, extending below the loop 12 and spaced from the box. The latch can be opened by pulling out the elbow, thereby swinging the loop 12 to the other side of the loop 14, overcoming an increased tension of the latch when the loop 12 passes over a line 18.

Open or inoperative positions of the latch are shown in Fig. 4, solid lines indicating its position when the latch member is pulled out and the hook 10 released, and dotted lines indicating position at rest when the latch member is hanging down under the base plate 6.

A diagrammatic view in Fig. 5 indicates forces acting on the latch member when the latter is being pressed into a locking position. It can be seen that because of the particular toggle arrangement of the parts, a force 20, acting on the elbow of the latch, as shown by an arrow 19, is considerably smaller than the force 21 which draws the lid against the box.

A screw 23 with a wing head 24 may be provided, passing through a hole in the latch 11 and threaded into the part 6. Such a screw will prevent any accidental opening of the latch member in handling.

The parts may be protected against being tampered in transit by a lead seal 25 on a wire 26, passing through a groove 27 in the base plate 6 and under the elbow 17.

It should be noted that the members 1 and 6 cannot be detached from the box without breaking the seal since the head of the screw 5 is partly covered by the hook 10, while the screw 8 is covered by the elbow 11.

My toggle catch can be used with any wooden boxes, especially such as are provided for transporting ammunition and similar articles. It can be also used for trunks, containers of various types, etc.

It is understood that my toggle catch may be further modified without departing from the spirit of my invention, as set forth in the appended claims.

I claim as my invention:

1. A toggle catch for a box comprising a base plate adapted to be attached by screws at its lower portion to the side of the box, the upper portion of the plate being bent outward and provided with a loop; a link made of heavy wire bent in the form of a rectangular ring rotatively held at one side in the loop; and a latch member having a loop at the lower end engaging the other side of the link, the upper end of the latch member having a hook adapted to engage a keeper on the lid of the box and to partly cover a screw fastening the keeper to the front portion of the lid, the intermediate portion of the latch member being bent downward from the loop, forming an elbow partly covering one of the fastening screws on the base plate and serving as a handle for the latch member, the latch member and the link forming a toggle joint for drawing the lid against the box.

2. A toggle catch for a box comprising a base plate adapted to be attached by screws at its lower portion to the side of the box, the upper portion of the plate being bent outward and provided with a loop; a link made of heavy wire bent in the form of a rectangular ring rotatively held at one side in the loop; and a latch member having a loop at the lower end engaging the other side of the link, the upper end of the latch member having a hook adapted to engage a keeper on the lid of the box and to partly cover a screw fastening the keeper to the front portion of the lid, the intermediate portion of the latch member being bent downward from the loop, forming an elbow partly covering one of the fastening screws on the base plate and serving as a handle for the latch member, the latch member and the link forming a toggle joint for drawing the lid against the box, the link being of a sufficient size to allow passage of the elbow upward therethrough for hanging the latch member downward when not engaged by the keeper.

3. A toggle catch for a box comprising a base plate adapted to be attached by screws at its lower portion to the side of the box, the upper portion of the plate being bent outward and provided with a loop; a link made of heavy wire bent in the form of a rectangular ring rotatively held at one side in the loop; and a latch member having a loop at the lower end engaging the other side of the link, the upper end of the latch member having a hook adapted to engage a keeper on the lid of the box and to partly cover a screw fastening the keeper to the front portion of the lid, the intermediate portion of the latch member being bent downward from the loop extending downward and outward with a sharp bend at the lowest point forming a handle, the latch member being bent at the middle to allow its loop to be moved nearer to the box than the loop on the base plate.

4. A toggle catch for a box comprising a base plate adapted to be attached by screws at its lower portion to the side of the box, the upper portion of the plate being bent outward and provided with a loop; a link made of heavy wire bent in the form of a rectangular ring rotatively held at one side in the loop; and a latch member having a loop at the lower end engaging the other side of the link, the upper end of the latch member having a hook adapted to engage a keeper on the lid of the box and to partly cover a screw fastening the keeper to the front portion of the lid, the intermediate portion of the latch member being bent downward from the loop, forming an elbow partly covering one of the fastening screws on the base plate and serving as a handle for the latch member, the latch member and the link forming a toggle joint for drawing the lid against the box, the base plate being bent in the middle to form a groove for a sealing wire.

HARRY D. GREENMAN.
